UNITED STATES PATENT OFFICE

132,426

DESIGN FOR A DUSTPAN

Edwin Morrison George, Republic, Wash.

Application February 10, 1942, Serial No. 105,744

Term of patent 3½ years

To all whom it may concern:

Be it known that I, Edwin M. George, a citizen of the United States, residing at Republic, in the county of Ferry and State of Washington, have invented a new, original, and ornamental Design for a Dustpan, of which the following is a specification, reference being had therein to the accompanying drawing, forming part thereof, in which—

Figure 1 is a perspective view of a dustpan, showing my new design.

Figure 2 is a bottom perspective view of said dustpan.

I claim:

The ornamental design for a dustpan, as shown.

EDWIN MORRISON GEORGE.
